UNITED STATES PATENT OFFICE.

OTTO F. REICH, OF CHICAGO, ILLINOIS, ASSIGNOR OF ONE-THIRD TO CHARLES E. CHURCH AND ONE-THIRD TO WILLIAM T. CHURCH, BOTH OF CHICAGO, ILLINOIS.

DESIGN FOR A GOLF TEE.

Application filed April 18, 1928. Serial No. 26,367. Term of patent 14 years.

To all whom it may concern:

Be it known that I, OTTO F. REICH, a citizen of the United States, residing at Chicago, in the county of Cook and State of Illinois, have invented a new, original, and ornamental Design for a Golf Tee, of which the following is a specification, reference being had to the accompanying drawing, forming part thereof,

Fig. 2 is a top plan thereof.

Fig. 3 is a bottom plan.

Fig. 4 is a side elevation of the same.

I claim:

The ornamental design for a golf tee as shown.

OTTO F. REICH.
